L. R. HECKER.
ATTACHMENT FOR CURRENT COLLECTOR WHEELS.
APPLICATION FILED JULY 13, 1907.

919,009.

Patented Apr. 20, 1909.

UNITED STATES PATENT OFFICE.

LEADDISON ROSS HECKER, OF PHILADELPHIA, PENNSYLVANIA, ASSIGNOR TO SAFETY ELECTRIC RAILWAY CONSTRUCTION COMPANY, OF PHILADELPHIA, PENNSYLVANIA, A CORPORATION OF THE DISTRICT OF COLUMBIA.

ATTACHMENT FOR CURRENT-COLLECTOR WHEELS.

No. 919,009.

Specification of Letters Patent.

Patented April 20, 1909.

Application filed July 13, 1907. Serial No. 383,702.

To all whom it may concern:

Be it known that I, LEADDISON Ross HECKER, a citizen of the United States, and resident of Philadelphia, in the county of 5 Philadelphia and State of Pennsylvania, have invented a certain new and useful Attachment for Current-Collector Wheels, of which the following is a specification.

The principal object of the present invention is to provide an attachment for current collector wheels, whereby electric currents that have performed their work may be returned to the power house by means of a rail, third rail or conduit.

15 A further object is to provide a simple, efficient and comparatively inexpensive attachment for this purpose.

Other objects will hereinafter appear.

To these and other ends hereinafter set 20 forth the invention stated in general terms comprises the improvements to be presently described and finally claimed.

The nature, characteristic features and scope of my invention will be more fully 25 understood from the following description taken in connection with the accompanying drawings forming part hereof, and in which—

Figure 1 is a sectional view of the attachment embodying the invention. Fig. 2 is a 30 similar view of a collector wheel illustrating the attachment embodying the invention in application thereto, and Fig. 3 is a side elevational view of the same.

In the drawings *a* is a tube flanged at one 35 end as at *b* and screw-threaded at its opposite end *c*.

d is a plug of insulation shown as being screw-threaded and incasing the tube *a*, and abutting against the flange *b* thereof and is 40 held in place by means of a lock nut *e* engaging the threaded end of the tube *a*.

Having screw threaded relation with the end of the tube *a* is a cap *f* tapped for the reception of an adjusting screw *g*, penetrating 45 the outer end of the tube *a*. *i* is a transmitting brush, preferably of carbon, movable within the tube *a* and having interposed between it and the adjusting screw *g* a tension spring *h*.

50 This device comprises a complete attachment and is especially adapted for application to collector wheels, shown and described

in an application filed by me jointly with Andrew H. Angle on the 13th day of July, 1907, Serial Number 383,701.

55

A brief description will now be given of the application of the attachment to such a collector wheel. 1 is a forked frame having journaled therein a collector wheel 2, adapted to contact with a charged rail 3 of a conduit 4. 5 are tire plates secured to and insulated from the collector wheel 2 and are adapted to travel along the top of the conduit 4. The insulation plug *d* is adapted to be fitted to the frame 1 in such manner that the transmitting 60 brush will contact with and press against the side of one of the tire plates as shown. The return wire *j* may then be connected to the end *c* of the tube *a*, and the cap *f* screwed down upon said return wire to effect, as it 65 were, a binding post. By this arrangement, it is obvious that current passes from the charged rail 3 of the conduit, through the wheel 2, shaft 6, spring contact 7, and frame 1, to the operating mechanism, not shown, 70 and after doing its required work, is returned by way of conductor *j*, tube *a*, brush *i*, tire plate 5, conduit 4, to the power house.

It will be borne in mind that while reference has been made herein to returning current 75 to the power house by a conduit, I do not wish to limit myself to such, as I have in mind returning current to any desired point by way of rails, third rails, or other manner as may be most convenient.

80

Having thus described the nature and objects of my invention, what I claim as new and desire to secure by Letters Patent, is—

85

1. A device of the class described, comprising a plug of insulating material, a tube 90 flanged at one end and screw-threaded at its opposite end carried by the plug, a lock nut upon the tube for forcing the flanged part of the tube against the plug, a screw-threaded and tapped cap for the end of the tube, an 95 adjusting screw carried by the cap, a transmitting brush within the tube, and a tension spring interposed between the said brush and adjusting screw.

2. A device of the class described comprising a screw-threaded plug of insulating material, a flanged and screw-threaded tube carried thereby, means carried by the upper 100 end of said tube for forcing the flanged part

of the tube against said plug, a cap engaging said screw-threaded tube, adjusting means carried by the cap and penetrating the said tube, a transmitting brush within the tube 5 and a cushion between said adjusting means and said brush.

In testimony whereof I have hereunto

signed my name this 20th day of June, 1907, in the presence of the subscribing witnesses.

LEADDISON ROSS HECKER.
